UNITED STATES PATENT OFFICE.

PERCY ABEL, OF ALTON, ILLINOIS.

KNIFE.

1,155,331.

Specification of Letters Patent.

Patented Oct. 5, 1915.

Application filed November 11, 1914. Serial No. 871,536.

To all whom it may concern:

Be it known that I, PERCY ABEL, a citizen of the United States, residing at Alton, in the county of Madison and State of Illinois, 5 have invented certain new and useful Improvements in Knives, of which the following is a specification, reference being had to the accompanying drawings.

This invention relates to new and useful 10 improvements in knives and more particularly to a lineman's knife, the main object of the present invention being the provision of a knife of the above character which is generally used by linemen for cutting the 15 insulation from wires when it is desired to connect the loose ends of two or more wires.

Another object of the present invention 20 is the provision of a cutting knife of the above character wherein the blade thereof is insulated from the handle and other parts 25 of the knife and the handle is provided with a ring, whereby the knife can be readily suspended from the belt of the operator.

A further object of the present invention 25 is the provision of a knife of the above character which will possess advantages in points of efficiency and durability, is inexpensive to manufacture and, at the same time, is simple in construction and operation.

30 With the above and other objects in view, the invention consists in the novel features of construction, combination and arrangement of parts as will be hereinafter referred to and more particularly pointed out in the 35 specification and claim.

In the accompanying drawing forming a 40 part of this application, Figure 1 is a longitudinal sectional view of a handle of a knife constructed in accordance with my invention; and Fig. 2 is a similar view taken at right angles to Fig. 1.

In carrying out my invention, I provide 45 a handle which is generally indicated by the numeral 1 and may be constructed of wood, hard rubber or any other material suitable for the purpose and preferably provided in two sections, 2 and 3. The blade which is indicated by the numeral 4, is formed of crucible steel and the shank thereof is provided with a pair of spaced openings adapted 50 to receive retaining bolts 5 which extend through the handle and through the openings in the shank, said bolts having the ends thereof counter-sunk as shown at 6, so that the hand of the operator will not come in contact with them. The sections of the han-

dle of the knife are provided at their inner ends with opposed recesses to receive the shank portion 6 of the ring 7, said ring projecting beyond the inner end of the handle 60 and adapted to be removably secured to the belt of the lineman or other operator, whereby it can be quickly and readily removed for use, or placed back in position.

The space which as indicated at 8 comprehended between the inner end of the blade 4 and the shank 6 of the ring, is filled with fiber or any other suitable insulating material 11 so as to insulate the ring from the knife blade. The insulation 11 incloses the 70 inner ends and sides of the ring shank, as shown in Fig. 1. In view of the fact that the securing bolts 5 are sunk into the handle at each end thereof, the hand of the operator will not come in contact with these 75 bolts and as the ring 7 is insulated from the knife blade, there will be no possibility of short-circuiting the wires. The shank 6 of the ring 7 is securely retained within the handle by means of the rivets 9 which extend through the handle and the shank 7 and are counter-sunk as shown at 10. From this it will be apparent that the outside of the handle will present a smooth and unbroken surface.

80 From the above description taken in connection with the accompanying drawing, it will be readily apparent that I have provided a simple and durable lineman's knife 85 which can be easily carried about and will take up comparatively little room. It will be noted that the ring 7 and the shank 6 thereof and the knife blade are arranged in the same plane so that when the knife is attached to the belt of the operator, the blade 90 thereof will lie flat against the operator's body, so that the operator will not be accidentally cut by the edge of the knife. Furthermore, by having the ring 7 secured to the outer end of the handle, this knife can 95 be readily carried about by the lineman without interfering with the other tools attached to his belt. My improved lineman's knife, as herein shown and described, is extremely simple in construction and can be manufactured and placed upon the market 100 at a comparatively low cost.

105 While I have shown and described the preferred form of my invention, it will be obvious that various changes in the details of construction and in the proportions may be resorted to successfully carrying my in-

vention into practice; without sacrificing any of the novel features or departing from the scope of the invention, as defined by the appended claim.

5 Having thus described this invention, what I claim as new and desire to secure by Letters Patent, is:—

A device of the class described including a handle consisting of two sections, a knife 10 blade having a shank arranged between the sections at one end thereof, a removable bolt extending through the handle and shank and having its ends counter-sunk within the sections, a ring provided with a 15 shank arranged between the sections of the

handle at the opposite end thereof, rivets extending through the handle and the shank and ring to rigidly secure the ring in position, and means for filling the space between the inner ends of the knife shank and the 20 shank of the ring, whereby to insulate the ring from the knife, as and for the purpose set forth.

In testimony whereof I hereunto affix my signature in the presence of two witnesses. 25

PERCY ABEL.
